GAME

Wilfrid Paul Heath, Seattle, Wash.

Application February 27, 1936, Serial No. 65,964

6 Claims. (CL 273—130)

My invention relates to games of the so-called "parlor" type and has to do more particularly with a game which involves a combination of chance and skill.

5 In accordance with my invention the game may be played in a large number of ways and various devices may be employed for the same, all embodying the same principle. It will be understood therefore that the devices which I have illustrated 10 and the methods of employing the same are merely exemplary and by no means limiting.

Referring now to the drawings forming a part of this specification and illustrating certain preferred embodiments of my invention:

15 Fig. 1 is a plan view of a game board embodying my invention;

Fig. 2 is a sectional view taken substantially along the line 2—2 of Fig. 1;

20 Figs. 3, 4 and 5 are perspective views of pieces used in connection with the game board for indicating targets or sectors; and

Fig. 6 is a side elevational view of an alternative form of game board embodying my invention.

An inspection of Fig. 1 will show that in one of its preferred forms my invention is applied to a "battleship" game wherein pieces are concealed by one player to represent ships in a fleet which is to be attacked by the opposing player, who has no knowledge of their disposition. The "attacking" player then proceeds to indicate certain sectors behind which he guesses the targets to be concealed. As the game proceeds, each player keeps a score of the "hits" or correct guesses of his opponent, which scoring enables his opponent, by deductive reasoning, to select his targets with increasing accuracy. The game, therefore, becomes an exciting test of mental adroitness combined with the element of chance.

While the drawings illustrate my invention as applied to a battleship game, it will be obvious that the same principles may be applied to a game wherein targets represent companies or regiments of soldiery rather than ships, or various other fanciful arrangements.

45 The game is especially adapted to be played on a horizontal surface and includes a board 10. Fig. 1 shows this board as adapted to be played simultaneously by two players, it being apparent that the various features on opposite sides of the line A—B are duplicates. This may be considered therefore as a double board wherein two opponents may proceed alternately against each other. However, according to one form of my invention, a game board may comprise only the parts on 50 one side of the line A—B, i. e., one-half of the board shown in Fig. 1. In using such a device, a game consists of an attack by one player and a defense by the other, after which the roles may be reversed.

60 A board comprises a plurality of parallel ele-

vations or ridges 12 separated by trenches or depressions 13. These depressions 13 are shown (Fig. 2) as triangular in cross section in order that they may house wedge shaped pieces as shown in Fig. 3, but said depressions may take numerous other forms so as to seat pieces of various other shapes and forms, such as cylindrical pieces shown in Fig. 4, or spherical pieces as shown in Fig. 5. The pieces may be formed of wood, metal, glass, or other suitable material, while the board may 10 conveniently be molded from papier maché or a suitable plastic. Arranged in the elevations or ridges 12 are a plurality of holes or cavities 15 which may be used by the attacking player to indicate a selection of a target by inserting a peg 16 in certain of said cavities 15. However, various other arrangements may be used to enable the attacker to indicate a selection of targets or sectors on the elevations 12. Thus for example, transverse lines may be marked on the ridges 12 20 dividing them into areas representing sectors behind which targets may be concealed, and the attacking player may place disks, buttons, or any other suitable type of marker on certain areas to indicate his choice of targets.

25 Communicating with all of the depressions 13 is a transverse trench or cavity 18, said communication trench 18 having an enlarged well portion 20. It is intended that pieces concealed in the various trenches 13 may be readily removed from 30 the board by tilting the latter toward the communication trench 18 or by pushing the pieces with a peg or the like toward the trench 18 and toward the well 20, from which the pieces may be readily extracted with the fingers.

35 A plurality of relatively shallow cavities 23 may be provided for pegs or the like to be used in playing the game, as hereinafter described.

To facilitate the keeping of score, the board is 40 also provided with means for registering "hits" made by the opposing player. Such means may comprise several series of cavities of the same or different number, as represented at 25, 26 and 27.

A preferred manner of playing the game will 45 now be explained, the board being arranged in a horizontal plane, as on a table.

It is arbitrarily taken that a battleship occupies a space equivalent to five consecutive targets, sectors or spaces on the board, a cruiser 4 and a destroyer 3. Of course, the objectives may 50 be of any desired number and may be assumed to occupy any space agreed on by the players. The number of objectives and the spaces they are to occupy should be agreed on. Preliminarily to playing the game, the defending player places 55 his pieces, which may be of any of the forms shown in Figs. 3—5, or of any other suitable form, in the trenches or depressions 13, laying down his pieces in any desired manner so long as they occupy consecutive positions on the board, either 60

longitudinally or transversely of the trenches 13. As shown in Fig. 1, it is assumed that the defending player has placed his pieces P at the positions indicated. It will be understood, of course, that the pieces are placed without the knowledge of the attacking player as to their location. This may be accomplished either by the attacker's looking aside, as the defender arranges his forces, or by the provision of a screen S in a slot 35, 10 when a double board is being used. In any event, after the pieces are placed behind the elevations 12, i. e., behind with relation to the vision of the attacking player, they will be effectively concealed from his view.

15 The attacker then proceeds to place his "shots" by applying markers on the various elevated sectors behind which he supposes the targets to be concealed. In the given embodiment, this is done by inserting pegs 16 in certain of the cavities 15. According to one manner of playing the game, the attacker is permitted five "shots" in a "salvo" or "broadside"; that is, he is permitted to place five markers in any given play, after which his "hits" are scored. A "hit" is registered by placing a marker on an area behind which a target or piece has been concealed by the defending player. The defending player thereupon proceeds to indicate the score achieved by his opponent's play.

20 It will be seen from the positions of the markers indicated on Fig. 1, which show an example of a single play or "salvo", that a "hit" has been accomplished against the defender's battleship, as indicated at 30, and also a "hit" against the cruiser, as indicated at 31. This is scored by inserting pegs 30' and 31' in the scoring devices 25 and 26, as indicated. The game is more interesting if each "salvo" is fired with pegs of a different color and the score indicated with pegs of the same color as the "salvo" which is scored. 25 With a double board as shown the defender will then proceed to attack his opponent in like manner and the players will continue alternately or simultaneously until "shots" have been placed 30 by a player in registry with all of the pieces representing his opponent's targets, whereupon the defending player may call out, "Cease firing". This will represent a game won by a particular player, which may be scored by placing pegs in 35 the apertures indicated in the positions 32.

35 It will be seen that a feature which adds considerably to the excitement of the game is the element of concealment of the pieces P from the attacker while, at the same time, they are visible to the defender. Thus, by observing the scoring and the positions of the shots previously fired, an attacker may deduce to a certain extent the disposition of his opponent's forces. Such deductions may be made with increasing accuracy as 40 the game proceeds.

45 In an alternative embodiment illustrated in Fig. 6 this feature of concealment is augmented by forming the upper surface of the board 16' in a mild curve instead of in a plane, as in the embodiment of Figs. 1 and 2. A slot may likewise be provided as at 35' in Fig. 6 in which a screen S' may be inserted.

50 Of course, the game may be simplified by eliminating the devices for indicating a selection of areas by the attacking player, such as the pegs 16. Thus, the attacker may merely indicate by

pointing to the areas behind which he guesses targets to be concealed; or the areas may be numbered or otherwise distinguished and the attacker may orally specify his choice. In such cases, scoring would probably have to be done as 5 the play proceeds.

Various other changes coming within the spirit of my invention may suggest themselves to those skilled in the art. Hence, I do not wish to be limited to the precise forms shown and described 10 herein except to the extent indicated in the appended claims which are to be interpreted as broadly as the state of the art will permit.

I claim:

1. A game board having indicated thereon a 15 plurality of playing stations arranged in parallel rows and having a depression adjacent each of said rows, a plurality of pieces disposable in said depressions, said pieces and said depressions being so shaped that the pieces are concealed by 20 the walls of said depressions from a player at one end of said board while being visible to a player at the opposite end thereof, and means for indicating a selection of certain of said playing stations by an opposing player. 25

2. A game board having a plurality of parallel grooves therein defining a series of elevations, said elevations each having a plurality of cavities therein, pieces disposable in said grooves, said pieces and said grooves being so shaped that the 30 pieces are concealable by the walls of said grooves, and a plurality of members engageable in said cavities.

3. A game board having a plurality of parallel grooves therein defining a series of elevations, 35 said elevations each having a plurality of cavities therein, pieces disposable in said grooves, said pieces and said grooves being so shaped that the pieces are concealable by the walls of said grooves, and a plurality of groups of members engage- 40 able in said cavities, each group being of a different color.

4. A game board having a plurality of playing stations indicated thereon, said board having a depression adjacent said playing stations, a piece 45 disposable in said depression, said piece and said depression being so shaped that the piece is concealed by the walls of said depression from a player at one end of said board while being visible to a player at the opposite end thereof, and 50 means for indicating a selection of certain of said playing stations.

5. A game board having indicated thereon a plurality of playing stations arranged in parallel rows and having a depression adjacent each of 55 said rows, a plurality of pieces disposable in said depressions, said pieces and said depressions being so shaped that the pieces are concealed by the walls of said depressions from a player at one end of said board while being visible to a player at the opposite end thereof, and means for indicating a selection of certain of said playing stations by an opposing player. 60

6. A game board having indicated thereon a plurality of playing stations arranged in parallel 65 rows and having a depression adjacent each of said rows, and a piece disposable in said depressions by a player, said piece and said depressions being so shaped that the piece is concealable by a wall of the depressions in which it is disposed. 70

WILFRID PAUL HEATH.
